UNITED STATES PATENT OFFICE

135,020

DESIGN FOR A DRESS

David E. Gottlieb, New York, N. Y.

Application January 13, 1943, Serial No. 109,253

Term of patent 3½ years

To all whom it may concern:

Be it known that I, David E. Gottlieb, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the dress shown in Fig. 1, illustrating the embroidery in detail.

The characteristic feature of my design resides in the combination on the dress disclosed of the specific embroidery arranged on the front portion of the specific dress as shown.

I claim:

The ornamental design for a dress, substantially as shown and described.

DAVID E. GOTTLIEB.
